MOTOR CONTROL SYSTEM

Joe White, Anderson, Ind., assignor to General
Motors Corporation, Detroit, Mich., a corpora-
tion of Delaware

Application September 7, 1942, Serial No. 457,564

7 Claims. (Cl. 172—239)

This invention relates to systems for a reversible servo-motor for operating a device such as an arm for steering a vehicle.

It is an object of the present invention to provide a controlling system including a quick acting relay for controlling the reversal of current through the motor armature. The advantage of using a quick acting relay will be more apparent from the following description of an embodiment of the invention.

Fig. 1 is a wiring diagram showing the various elements of the system and their electrical connections.

Fig. 2 is a diagram similar to Fig. 1, with certain elements of the device, however, in different positions and effect from that shown in Fig. 1.

Fig. 3 is a similar view to Fig. 2 showing other elements of the system in another position.

An electric motor M having a field F and an armature A is connected for rotation in one direction with the positive line 10 and the negative line 11 of a current source 5 through the following circuit; switch 12, wire 13, contact 14, contact 15, wire 16, armature A, wire 17, contact 18, contact 19, wire 20, field F, and negative line 11. This causes flow of current through the field in the direction indicated by arrow 45 and through the armature as indicated by arrow af. The motor drives shaft 25 through a speed reducing gear unit 26. Shaft 25 operates an arm 27 connectible with a device to be operated, such as the steering mechanism of a vehicle. Arm 27 may stand in a normal, or center position 27c or in extreme left position 27L or in extreme right position 27R or in intermediate positions.

The contacts 14, 15, 18 and 19 are part of a relay unit 30 comprising a core 31, surrounded by a winding 32 of relatively fine wire such as 1,000 turns of #33 gauge wire and surrounded by a winding 34 of relatively coarse wire such as 1,000 turns of #24 gauge wire. Winding 32 is connected at junction 33 with winding 34 and with negative line 11. Winding 34 is connected by wire 35 with wire 17 and with a contact 36 normally disconnected from contact 37. Relay 30 has a contact 38 normally out of engagement with a contact 39 and connected by wire 40 with wire 16. Contacts 14 and 37 are electrically connected and contacts 19 and 39 are electrically connected. These contacts are insulatingly supported by an armature 41 normally held by a spring 42 away from the relay core 31.

The shaft 25 carries an arm 51 of a limit switch unit 50. Arm 51 carries a non-conducting stud 52 for engaging either of two resilient blade arms 53 or 54 carrying, respectively, contacts 55 and 56. Contact 55 normally engages a contact 57 carried by blade 59, electrically connected with blade 54 and electrically connected by wire 61

with the junction 33 of relay coils 32 and 34. Contact 56 is normally separated from contact 58 on blade 60 which is connected by wire 62 with wire 13. Wire 10 is connected by switch 63 with blade 53.

To effect rotation of arm 27 from the position 27c clockwise toward the position 27L, only switch 12 is closed and the motor operates with the circuit shown in heavy lines in Fig. 1. Current flows through armature A as indicated by the arrow af and through the field F as indicated by the arrow 45. The flow in relay coils 32 and 34 is indicated by the arrow heads thereon and their effects are bucking as indicated by oppositely pointing arrows 32a and 34a in Fig. 1.

To effect rotation of arm 27 counterclockwise toward position 27R, the switch 63 as well as switch 12 is closed to cause first a reversal of current in relay coil 34 as indicated by arrow heads on this coil in Fig. 2. The effect is to place coil 34 in assisting relation to coil 32 as indicated by arrows 32a and 34b pointing in the same direction. Relay armature 41 is attracted toward the core 31 and the motor reversing circuit is completed as shown in Fig. 3. Direction of field current flow remains unchanged as indicated by arrow 45 in Fig. 3, but armature current flow is reversed as indicated by arrow ar. The movement of armature 41 into the position shown in Fig. 3 causes coil 34 to be short circuited and coil 32 alone remains effective as indicated by arrow 32a to hold the armature 41 in attracted position since the air gap between the armature and core has been reduced. When the control system is in the status shown in Fig. 2, coil 34 is connected with wire 10 through switch 63, limit switch contacts 55, 57 and wire 61, and is connected with wire 11 through wire 35, wire 17, contacts 18, 19 and field F. When the control system is in the status shown in Fig. 3, coil 34 is short-circuited by the closing of contacts 37, 36 thus placing both ends of coil 34 at the same voltage.

Rotation of arm 27 counterclockwise will continue so long as switch 63 as well as switch 12 remains closed, but no further than required for arm 51 to engage blade 53 to separate contact 55 from contact 57. This separation has the same effect as opening switch 63, namely, to effect deenergization of the relay in the following manner: The status of coil 34 changes from a condition of being short-circuited and inactive to a condition of being in bucking relation to coil 32 thus quickly deenergizing the relay and causing the relay armature 41 to return to the position shown in Fig. 1, thereby causing the motor to rotate the arm 27 clockwise and contacts 55 and 57 to engage whereupon the arm 27 again rotates counterclockwise; and this cycle is repeated so long as switch 63 remains closed while switch

12 remains closed. Therefore the arm 27 oscillates through a very small angle while in the position 27R. This angle of oscillation is small because the operation of relay 30 is rapid. This rapidity is due to the fact that the status of coil 34 is changed from bucking to assisting to effect movement of the armature 41 toward the core; and the status of coil 34 is changed from non-operating to bucking to cause rapid counteraction of the armature holding flux of coil 32 to permit quick return of the armature 41 by the spring 42.

The repetition of the same cycle occurs when arm 27 has rotated clockwise to position 27L as result of closing only switch 12 to complete the circuit shown in heavy lines in Fig. 1. Upon the arrival of arm 27 at 27L, stud 52 of arm 51 has engaged blade 54 and has caused contact 56 to engage 58. There is first a counterclockwise rotation of arm 27 sufficient to permit opening of contacts 56 and 58 and then a clockwise rotation of arm 27 sufficient to close these contacts. This cycle is repeated so long as switch 12 remains closed or until switch 63 is closed while switch 12 remains closed. The angle of oscillation of arm 27 at position 27L is small because the relay 30 is quick acting for reasons already given.

One advantage of this system is that only one relay is required. The switch 12 is the main control switch and also the switch which, when closed alone, causes clockwise rotation of the arm 27 toward the 27L position. When arm 27 has moved as far as 27L it will move no further in a clockwise direction. If it is desired to stop the arms 27 between 27C and 27L, the operator opens switch 12. If it is desired that the arm 27 should move counterclockwise toward the 27R position the switch 63 is closed while switch 12 remains to cause the relay 30 to reverse the operation of the motor. So long as switch 63 remains closed while switch 12 is closed, the arm 27 will move to position 27R but no further. If it is desired to stop movement of arm 27 in a counterclockwise direction before arriving at 27R, both switches 12 and 63 are opened. If it is desired to cause arm 27 to move clockwise immediately after having moved counterclockwise, only the switch 63 is opened. If the arm is oscillating at position 27L and it is desired to move to 27R, the switch 63 is closed while switch 12 remains closed. If the arm is oscillating at position 27R and it is desired to move the arm to position 27L, then only is switch 63 opened while switch 12 remains closed. If it is desired to move the arm from 27R to 27C, switches 12 and 63 being closed, switch 63 is opened and switch 12 remains closed until the arm arrives at 27C, and then switch 12 is opened. If it is desired to move the arm from 27L to 27C, switch 12 being closed, switch 63 is also closed until the arm arrives at 27C and then switch 12 is opened. Both switches are opened when use of the control system is discontinued.

While the embodiment of the present invention as herein disclosed, constitutes a preferred form, it is to be understood that other forms might be adopted, all coming within the scope of the claims which follow.

What is claimed is as follows:

1. A motor control system comprising a current source, an electric motor having a field and an armature, a rotatable member operated by the motor, a circuit for connecting the source and motor for rotation of the member in one direction and including a manually closed switch and pairs of normally closed contacts, a circuit for connecting the source and motor for rotation of the member in the opposite direction and including said manually closed switch and pairs of normally closed contacts, a relay electromagnet having an armature for opening the normally closed contacts and for closing the normally open contacts, and having an armature main attracting winding and an armature holding winding, said windings being normally in bucking relation, a normally open limit switch and a circuit completed by the closing thereof for causing the windings to be placed in assisting relation to effect the attraction of the relay armature, means operated by the motor, and responding to movement of the member in the first mentioned direction to a certain position for closing the limit switch, and a short circuit of the armature main attracting winding established in response to the attractive movement of the armature, the attraction movement of the armature causing the motor to operate in said opposite direction to allow the limit switch to open, whereupon the relation of the relay windings becomes bucking and the relay armature returns to normal position and the motor rotates in the direction first mentioned, and the cycle is repeated so long as the manually operated switch remains closed, whereby the member oscillates through a small angle at said certain position.

2. A motor control system comprising a current source, an electric motor having a field and an armature, a rotatable member operated by the motor, a circuit for connecting the source and motor for rotation of the member in one direction and including a manually closed switch and pairs of normally closed contacts, a circuit for connecting the source and motor for rotation of the member in the opposite direction and including said manually closed switch and pairs of normally closed contacts, a relay electromagnet having an armature for opening the normally closed contacts and for closing the normally open contacts, and having an armature main attracting winding and an armature holding winding, said windings being normally in bucking relation, a normally open limit switch and a circuit completed by the closing thereof for causing the windings to be placed in assisting relation to effect the attraction of the relay armature, means operated by the motor, and responding to movement of the member in the first mentioned direction to a certain position for closing the limit switch, and a short circuit of the armature main attracting winding established in response to the attractive movement of the armature, the attraction movement of the armature causing the motor to operate in said opposite direction to allow the limit switch to open, whereupon the relation of the relay windings becomes bucking and the relay armature returns to normal position and the motor rotates in the direction first mentioned, and the cycle is repeated so long as the manually operated switch remains closed, whereby the member oscillates through a small angle at said certain position.

3. A motor control system comprising a current source, an electric motor having a field and an armature, a rotatable member operated by the motor, a circuit for connecting the source and motor for rotation of the member in one direction and including a manually closed switch and pairs of normally closed contacts, a circuit for connecting the source and motor for rotation of the member in the opposite direction and including said manually closed switch and pairs of normally closed contacts, a relay electromagnet having an armature for opening the normally closed contacts and for closing the normally open contacts, and having an armature main attracting winding and an armature holding winding, said windings being normally in bucking relation, a circuit for causing the relay windings to be placed in assisting relation and comprising a second manually closed switch and a normally closed limit switch, whereupon the relay armature is attracted to effect reversal of direction of current flow through the armature, whereby the motor is caused to rotate the member in said opposite direction, a short circuit of the armature main attracting winding established in response to the attractive movement of the armature, and means operated by the motor and responding to movement of said member in said opposite direction to a certain position for opening the limit switch whereupon the relation of the relay windings becomes bucking and the relay returns to normal status and the motor rotates the member in the first mentioned direction and the limit switch recloses to effect operation of the relay to cause the motor to reverse and open the limit switch, this cycle being repeated so long as the second manually operated switch is closed, whereby the member is caused to oscillate through a small angle at the said certain position.

4. A motor control system comprising a current source, an electric motor having a field and an armature, a rotatable member operated by the motor, a circuit for connecting the source and motor for rotation of the member in one direction and including a manually closed switch and pairs of normally closed contacts, a circuit for connecting the source and motor for rotation of the member in the opposite direction and including said manually closed switch and pairs of normally closed contacts, a relay electromagnet having an armature for opening the normally closed contacts and for closing the normally open contacts, and having an armature main attracting winding and an armature holding winding, said windings being normally in bucking relation, a normally open limit switch and a circuit completed by the closing thereof for causing the windings to be placed in assisting relation to effect the attraction of the relay armature, means operated by the motor, and responding to movement of the member in the first mentioned direction to a certain position for closing the limit switch, and a short circuit of the armature main attracting winding established in response to the attractive movement of the armature, the attraction movement of the armature causing the motor to operate in said opposite direction to allow the limit switch to open, whereupon the relation of the relay windings becomes bucking and the relay armature returns to normal position and the motor rotates in the direction first mentioned, and the cycle is repeated so long as the manually operated switch remains closed, whereby the member oscillates through a small angle at said certain position.

for connecting the source and motor for rotation of the member in the opposite direction and including said manually closed switch and pairs of engageable normally open contacts, a relay electromagnet having an armature for opening the normally closed contacts and for closing the normally open contacts and having an armature main attracting winding and an armature holding winding, said winding being normally in bucking relation, a first circuit for causing the relay windings to be placed in assisting relation and including a normally open limit switch, a second circuit for causing the relay windings to be placed in assisting relation and including a normally closed limit switch and a second manually closed switch, the placing of said relay windings in assisting relation causing the attraction of the relay armature to a position for causing the motor to rotate the member in said opposite direction, a short circuit of the armature main attracting winding established by the attractive movement of the relay armature, means operated by the motor and responding to movement of said member in said first mentioned direction to a certain first position for closing the normally open limit switch and means operated by the motor and responding to movement of said member in said opposite direction to a certain second position for opening the normally closed limit switch, whereby when the first mentioned manual switch is closed and the other manual switch is open the motor will cause the member to move to said certain first position and there to oscillate through a small angle, or when both manually operated switches are closed, the motor will cause the member to move to said certain second position and then to oscillate through a small angle.

4. A motor control system comprising a current source, an electric motor, a relay having an armature and an electromagnet for attracting the armature and having an armature main attracting coil and an armature holding coil normally in bucking relation, first manually closed switch, a circuit completed by the first manual switch and the relay armature when in normal position for causing the motor to rotate in one direction, a circuit completed by the first manual switch and the relay armature when in attracted position for causing the motor to rotate in the opposite direction, a normally open first circuit for causing the relay windings to be in assisting relation and having a normally open limit switch closed upon certain rotation of the motor in the said first mentioned direction, a second circuit for causing the relay windings to be placed in assisting relation and having a manually closed switch and a normally closed limit switch opened upon a certain rotation of the motor in said opposite direction, the placing of the relay windings in assisting relation causing the electromagnet to attract the armature to cause the motor to rotate in said opposite direction, and a short circuit of the armature main attracting winding established by the attractive movement of the armature, the interruption of the circuits which placed the relay windings in assisting relation causing the relation of the relay windings to return to the normal bucking relation from a condition in which only the holding winding was effective.

5. A control device for an electric motor hav-

- ing armature and field circuits; means for connecting said circuits to a source of electric power to effect motor operation in either direction, said means comprising an electromagnetic relay provided with an armature which, when in normal, biased position, completes motor circuits for motor operation in one direction, and when in its attracted position completes motor circuits for motor operation in the opposite direction, said relay having a magnet winding for moving the armature out of its biased into its operated position; a power switch for connecting the relay armature with the power source to render the motor operative; a second winding on the relay for neutralizing the effect of the first mentioned relay winding when only said power switch is closed; and a second switch for connecting said second winding with the power source to render said second winding ineffective as a neutralizing winding and effective to cooperate with the first mentioned winding while the first switch is closed, for attracting the relay armature from its biased position and change motor connections to reverse its operation.
6. A control device for an electric motor having field and armature circuits means for connecting said motor circuits to a source of electric power to effect rotation of the motor in either direction, said means comprising, a two position electromagnetic switch adapted when in normal biased position to complete motor connections for one directional rotation and when moved from its biased into the attracted position to change connections for motor rotation in the opposite direction; a power switch for connecting the relay with the power source; two windings on the electromagnet connected to the power source to oppose each other and render the relay inactive when said power switch is closed; a second switch adapted to connect one of said windings with the power source in such a manner as to render it effective to assist the other winding in rendering the electromagnet active for changing motor connections and reversing its rotation; limit switches electrically connected with said other switches; and motor driven means for actuating the limit switches to control the operation of the motor in either direction within predetermined limits.
7. A control device for a reversible electric motor having field and armature circuits; a source of electric power, an electromagnet switch having two magnet windings and a contactor shiftable to reverse the armature circuit connection with one end of the field circuit; a control switch, when closed, connects the source of power with the motor field and armature circuit through the electromagnet switch contactor and with the magnet windings to energize them to have a bucking effect and thus be ineffective to actuate the contactor whereby the motor operates in one direction; and a second control switch, which, when closed while the first mentioned control switch is closed, completes a reverse current flow through one of the said magnet windings, rendering it effective to cooperate with the other magnet winding to actuate the electromagnet switch contactor from its normal to its operated position in which it reverses the connection of the armature circuit with the field circuit of the motor to effect reverse rotation of the motor.
